UNITED STATES PATENT OFFICE

SAMUEL M. WINKLER, OF NEW YORK, N. Y.

DESIGN FOR EMBROIDERED LACE

Application filed May 9, 1929. Serial No. 31,154. Term of patent 3½ years.

To all whom it may concern:

Be it known that I, SAMUEL M. WINKLER, a citizen of the United States, residing at 251 West 71st Street, in the city, county, and State of New York, have invented a new, original, and ornamental Design for Embroidered Lace, of which the following is a specification, reference being had to the accompanying drawing, forming part thereof.

The figure is a plan view of embroidered lace showing my new design.

I claim:

The ornamental design for an embroidered lace as shown.

SAMUEL M. WINKLER.
